UNITED STATES PATENT OFFICE.

DAVID ALCORN, JR., AND ROBERT A. BLAKE, OF NEW YORK, N. Y.

CORSET-STEEL FASTENING.

SPECIFICATION forming part of Letters Patent No. 326,259, dated September 15, 1885.

Application filed June 1, 1885. (No model.)

To all whom it may concern:

Be it known that we, DAVID ALCORN, Jr., and ROBT. A. BLAKE, of the city, county, and State of New York, have invented a new and useful Improvement in Corset-Steel Fastenings; and the following is declared to be a description of the same.

Our present invention relates to improvements upon the device described and claimed in Letters Patent granted to us May 12, 1885, No. 317,699.

The object of our present invention is to provide, in connection with the ordinary corset-fastening, a swinging plate which shall act to prevent the accidental unfastening of the corset-steels, and to lock the necks of the studs upon one steel into the eye-plates upon the other steel, and these swinging or locking plates are so constructed that the upward movement is limited by contact with one of the rivets that hold the eye-plates to the steel, and the downward movement is also limited by a projection upon the locking-plate coming in contact with a rivet or stop.

In the drawings, Figure 1 is an elevation of the upper part of a pair of corset-steels with our improvement shown thereon. Fig. 2 is a sectional plan at the line $x-x$ of Fig. 1. Fig. 3 is an elevation of part of a pair of steels as being fastened. Figs. 4 and 5 are elevations embodying slight modifications in the locking-plate.

A B represent a pair of corset-steels, to one of which are riveted eye-plates C, to engage with the studs D upon the other steel. The eyes of the plates are at their inner ends of sufficient size to allow the heads of the studs D to pass through, and are only large enough at their outer ends to receive the necks or shanks of said studs. The eye-plates C and studs D are riveted to the steels A B.

The locking swinging plates E are usually of the shape shown in Fig. 1, and are pivotally connected to the eye-plates C or steel A by a riveted pin, a, and upon the outer ends of said plates E there are thumb knobs or projections b, for convenience in raising or lowering the said plates in fastening or unfastening the corset-clasp. These plates E are

formed with recesses at 1, inclines at 2 and 3, 50 and recesses at 4, and the stops or projections c are also a part of said plates E.

In the position of the upper clasp in Fig. 1 the plate E is elevated, its upper edge coming in contact with the rivet 5, thus limiting 55 its upward movement, and in the lower clasp of Fig. 1, as depressed and locked, the stop c is brought against the same rivet 5, and the downward movement is thus limited, this stop being especially available when the corset is 60 unclasped to prevent the plate E dropping too far.

In the position shown in Fig. 3 the corset is about to be clasped with the plate E depressed, and the neck of the stud D, pressing 65 against the incline 3, raises the plate E, which is afterward pushed down to place, the incline 2, acting against the neck of the studs D to press it to place, and the recess 1 receiving 70 said neck and locking the stud between it and the end of the slot in the eye-plate C.

In Figs. 4 and 5 the stop or projection c is shown upon the under side of the plate E, stopping against the rivet 6, and in Fig. 5 the plate E is shown as pivotally connected to 75 the steel A by pin 7, the said plate being continued out beyond the edge of the eye-plate C, so as to be connected to the steel.

We claim as our invention—

1. The corset-steels and eye-plate and rivets having projecting heads connecting said eye-plate to one of the steels, and a stud upon the other steel, in combination with a latch-plate, a pivot for the same adjacent to the rivets of the eye-plate, and having the recess 85 in the outer end to receive and lock the stud, and a stop or projection on the plate, near the pivot thereof, to take against one of the eye-plate rivets to limit the downward movement of the plate, substantially as set forth. 90

2. The corset-steels A and B, the stud D on the steel B, the eye-plate C, and rivets with projecting heads for securing said eye-plate to the steel A, in combination with the latch-plate E, a pivot for the same near the rivets 95 that attach the eye-plate, so that said rivets limit the movement of the latch-plate in each direction, said latch-plate having a thumb-

knob at the outer end, and a recess, 1, and incline 2 below said recess, substantially as and for the purposes set forth.

3. The combination, with the corset-steels A B, eye-plate C, and stud D, of a pivotally-connected plate, E, stops to limit the movement in both directions, said plate having an incline at 3 to be automatically operated in clasping the corset, and a recess for locking the stud D, substantially as specified.

Signed by us this 26th day of May, A. D. 1885.

DAVID ALCORN, JR.
ROBT. A. BLAKE.
